DISPLAY DEVICE FOR HOUSE NUMBERS
AND THE LIKE

John Mitchell, Chicago, Ill.

Application November 6, 1948, Serial No. 58,686

5 Claims. (Cl. 40—132)

1

This invention relates to a display device for house numbers and the like, and relates particularly to an illuminated display device.

Display devices for house numbers and the like are sometimes constructed of a base member having means thereon for attaching number plates so that the correct number can be made by assembling a base plate and the proper number plates. Some of these display devices have included means for illuminating the numbers so that they become visible at night. The present invention is concerned with an improved display device comprising a base plate having at least one opening therein, a number plate extending across said opening and at least one improved holding member attached to the base plate and located adjacent to one edge of the number plate. This holding member includes a pair of extended fingers arranged on opposite sides of the number plate to prevent substantial lateral displacement thereof and a lip overlying at least a portion of the side of the number plate that is opposite the base plate to prevent substantial displacement of the number plate away from the base plate. The holding member or members may be readily attached to the base plate and will positively lock the number plates in position. If desired, the number plate or plates may be transparent at a portion thereof to define a number. Where this type of plate is illuminated an electric light may be located behind the base plate and number plate so that the light will shine through the transparent portion.

In a preferred construction, the base plate is provided with a box-like structure on the rear thereof having an open side normally closed by the base plate. This box-like structure is preferably removably held in place by providing flanges on adjacent opposite sides of the base plate, with these flanges adapted to engage frictionally corresponding sides of the box-like structure and hold this structure and the base plate in assembled relationship. Where the display device is illuminated, the illuminating means may be located within the box-like structure. In a preferred construction, this illuminating means comprises an electric bulb adapted to be held in a socket which is mounted on a clamp, with this clamp being held upon a flange located within the box-like structure. The clamp may be a spring clamp and the flange may be formed of a tongue struck from the material of the box-like structure.

One of the features of this invention is to pro-

2

vide a display device for house numbers and the like comprising a base plate having at least one opening therein together with a number plate extending across the opening and an improved holding member attached to the base plate for holding the number plate in position; another feature of the invention is to provide such a structure wherein the rear side of the base plate is covered by a removable box-like structure preferably held in place thereon by frictional engagement with a pair of flanges located on the rear of the base plate; still another feature of this invention is the provision of such a structure wherein illuminating means are provided within the box-like structure for illuminating the numbers. Other features and advantages of the invention will become apparent in the following description of one embodiment thereof taken in conjunction with the accompanying drawings.

20 Of the drawings:

Fig. 1 is a front elevation of a display device for house numbers and the like embodying the invention.

Fig. 2 is a longitudinal section taken through 25 the device of Fig. 1 and looking toward the rear surfaces of the number plates and the base plate.

Fig. 3 is a section taken along line 3—3 of Fig. 2.

Fig. 4 is a section taken along line 4—4 of 30 Fig. 2.

Fig. 5 is a section taken along line 5—5 of Fig. 2.

The display device shown in the accompanying drawings comprises a base plate 10 having a 35 plurality of spaced openings 10a therein arranged side by side longitudinally of the plate 10, and a plurality of number plates 11 with each number plate positioned across an opening and having marginal portions extending over the marginal areas of the base plate that are around the openings. The openings 10a have their top edges substantially aligned and their bottom edges also substantially aligned. Each number plate 11 is positioned against the rear surface of the base 40 plate 10 and is so held that the numeral portion 11a thereof is visible through the corresponding plate opening 10a.

The rear surface of the base plate 10 is provided with a pair of rearwardly extended flanges 50 12 arranged at substantially right angles to the base plate. Each flange is arranged adjacent the end edge of an opening 10a and the flanges are substantially parallel to each other. In order to lock the number plates 11 in position, there are provided a pair of holding members 13 adja-

cent the top and bottom edges of the number plates 11. Each holding member 13 is preferably constructed of a single piece of sheet metal and is provided with a plurality of lateral portions 13a with each lateral portion adapted to abut against the adjacent end of a number plate and prevent substantial displacement of the number plate in a direction toward the holding member. Each holding member is also provided with a plurality of extended fingers 13b with each finger being positioned between an adjacent pair of number plates to prevent substantial lateral displacement of the number plates toward each other. There is also provided a plurality of lips 13c on each holding member 13, with each lip overlying a portion of the side of a number plate that is opposite the base plate 10 to prevent substantial displacement of the number plate away from the base plate.

As is shown in the drawings, the lateral portions 13a, extended fingers 13b and lips 13c are made integral with the remainder of the holding member and the entire holding member including these portions may be made from a single sheet metal stamping. Each holding member 13 is also provided with means for locking the holding member in place. In the embodiment shown, this locking means comprises a portion 13d on the end of the holding member with this portion extending through a slot in a flange 12 and then bent up against the flange. This portion 13d prevents longitudinal movement of the holding member 13. In order to prevent lateral movement there is provided another portion 13e on the inner side of each holding member and bent around a small section 12a of metal displaced from a flange 12. The portion 13e locked around the section 12a prevents lateral displacement of the holding member 13 in a direction away from the openings 10a. Displacement of the holding member in a direction toward the openings is prevented by the portion 13d which engages the slot in the flange 12.

Each flange 12 is provided with an inwardly directed pin 14, upon which is mounted an annular resilient member 15. Each annular resilient member is positioned against the inner surface of a flange 12 in contact with the adjacent edge of a number plate 11. These resilient members are each provided with an annular groove 15a on the outer surface thereof so that they can be easily compressed. As these annular members bear against the end number plates, they permit considerable tolerances in the widths and location of the extended fingers 13b. In the embodiment shown, there are no fingers 13b adjacent the outer edges of the outer number plates 11. Thus, the number plates in a series of display devices may be separated by varying distances without harm as the resilient members 15 always bear against the outer edges of the end number plates.

In the embodiment shown, the display device includes a box-like structure 16 having an open side normally closed by the base plate 10, as shown in Figs. 2 to 5, inclusive. This structure 16 is normally held in place by frictional engagement of the ends 16a thereof with the flanges 12. In order to aid in maintaining this engagement, each end 16a is provided with an opening 16b adapted to hold the outer rounded head of the pin 14 on which the annular resilient member 15 is mounted.

In the preferred construction, the number plates 11 are made of glass with the numeral por-

tion 11a of each number plate being raised, as shown in Fig. 5, and the areas surrounding the numeral portion being covered with an opaque material such as black paint. The inner surface of each numeral portion 11a is preferably provided with a knobbed surface, as shown in Figs. 2 and 5, so as to provide for better light diffusion.

In order to illuminate the display device of this invention, there is provided an electric light bulb 17 within the box-like structure 16 and located substantially centrally thereof. This light bulb 17 is held in a socket 18 mounted upon a spring clamp 19. This spring clamp is removably held on a flange 20, as shown in Fig. 4. This flange may be formed of a tongue struck from the material which comprises the rear wall of the box-like structure 16. The socket 18 is provided with an electric cord 21 extending through an opening at the bottom of the box-like structure 16 with this opening preferably being provided with a rubber grommet 22.

In order that the display device may be suspended from a wall or other base member, there is provided a hole through the rear wall of the box-like structure 16 with this hole being located substantially midway between the ends of the structure and near the top thereof. In a preferred construction, this hole is provided with a rubber grommet 23. A nail or other suspending means may be used with this suspending means extending through the opening in the grommet.

From the above description of one embodiment of the invention, it is believed apparent that the invention provides a relatively simple display device in which one or a plurality of number plates are held so as to make an easily visible number. In the embodiment shown, four separate number plates are employed to display a number having four numerals. The same device, however, could be employed to display one, two, or three numerals. If less than four numerals were used, those openings 10a which were not used to hold a number plate could be closed by a light impervious plate. Thus, with the device of this invention, as many numerals may be provided as desired by providing a base plate having the required number of openings therein. Any number of numerals smaller than the maximum could be employed by merely closing off the unwanted openings.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. A display device for house numbers and the like, comprising: a base plate having a plurality of spaced openings therein arranged side by side and extending longitudinally of the plate, said openings having one of their ends substantially aligned, and said base plate having a flange opposite each end of the series of aligned openings with both flanges being on the same side of the base plate, each of said flanges being adjacent an end opening; a plurality of number plates with each number plate positioned across an opening and having marginal portions extending over marginal portions of the base plate around said opening, said number plates being located on the same side of said base plate as said flanges and located between said flanges; and a holding member located against the base plate and ad-

jacent said aligned ends of the openings, said holding member including a plurality of lateral portions each adapted to abut against the adjacent end of one of said number plates and prevent substantial displacement of the number plate in a direction toward the holding member, a plurality of extended fingers adjacent the edges of said number plates with a finger being located between an adjacent pair of number plates to prevent substantial lateral displacement thereof toward each other, and lips with each lip overlying at least a portion of the side of a number plate that is opposite the base plate to prevent substantial displacement of said number plate away from the base plate, and said holding member including an end portion extending through an opening in a flange and bent up to prevent longitudinal displacement of the member and a lateral portion bent around an extended portion on said flange to prevent lateral displacement of said member.

2. A display device for house numbers and the like, comprising: a base plate having a plurality of spaced openings therein arranged side by side and extending longitudinally of the plate, said openings having one of their ends substantially aligned, and said base plate having a flange opposite each end of the series of aligned openings with both flanges being on the same side of the base plate, each of said flanges being adjacent an end opening; a plurality of number plates with each number plate positioned across an opening and having marginal portions extending over marginal portions of the base plate around said opening, said number plates being located on the same side of said base plate as said flanges and located between said flanges; a holding member attached to said flanges and located against the base plate and adjacent said aligned ends of the openings, said holding member including a plurality of lateral portions each adapted to abut against the adjacent end of one of said number plates and prevent substantial displacement of the number plate in a direction toward the holding member, a plurality of extended fingers adjacent the edges of said number plate with a finger being located between an adjacent pair of number plates to prevent substantial lateral displacement thereof toward each other, and lips with each lip overlying at least a portion of the side of a number plate that is opposite the base plate to prevent substantial displacement of said number plate away from the base plate; and a resilient member attached to each flange and bearing against the adjacent side of the adjacent number plate.

3. A display device for house numbers and the like, comprising: a base plate having a plurality of spaced openings therein arranged side by side and extending longitudinally of the plate, said openings having their top and bottom ends substantially aligned, and said base plate having a flange opposite each end of the series of aligned openings with both flanges being on the same side of the base plate, each of said flanges being adjacent an end opening; a plurality of number plates with each number plate positioned across an opening and having marginal portions extending over marginal portions of the base plate around said opening, said number plates being located on the same side of said base plate as said flanges and located between said flanges; and a pair of holding members attached to said flanges and located against the base plate and adjacent each series of said aligned ends of the

openings, each of said holding members including a plurality of lateral portions each adapted to abut against the adjacent end of one of said number plates and prevent substantial displacement of the number plate in a direction toward the holding member, a plurality of extended fingers adjacent the edges of said number plate with a finger being located between an adjacent pair of number plates to prevent substantial lateral displacement thereof toward each other, and lips with each lip overlying at least a portion of the side of a number plate that is opposite the base plate to prevent substantial displacement of said number plate away from the base plate.

4. A display device for house numbers and the like, comprising: a base plate having a plurality of spaced openings therein arranged side by side and extending longitudinally of the plate, said openings having their top and bottom ends substantially aligned, and said base plate having a flange opposite each end of the series of aligned openings with both flanges being on the same side of the base plate, each of said flanges being adjacent an end opening; a plurality of number plates with each number plate positioned across an opening and having marginal portions extending over marginal portions of the base plate around said opening, said number plates being located on the same side of said base plate as said flanges and located between said flanges; a pair of holding members located against the base plate and adjacent each series of said aligned ends of the openings, each of said holding members including a plurality of lateral portions each adapted to abut against the adjacent end of one of said number plates and prevent substantial displacement of the number plate in a direction toward the holding member, a plurality of extended fingers adjacent the edges of said number plate with a finger being located between an adjacent pair of number plates to prevent substantial lateral displacement thereof toward each other, and lips with each lip overlying at least a portion of the side of a number plate that is opposite the base plate to prevent substantial displacement of said number plate away from the base plate, said holding members including an end portion extending through an opening in each flange and bent up to prevent longitudinal displacement of the member and a lateral portion bent around an extended portion on each flange to prevent lateral displacement of said member; and a resilient member attached to each flange and bearing against the adjacent side of the adjacent number plate.

5. An illuminated display device for house numbers and the like, comprising: a base plate having a plurality of spaced openings therein arranged side by side and extending longitudinally of the plate, said openings having one of their ends substantially aligned, and said base plate having a flange opposite each end of the series of aligned openings with both flanges being on the same side of the base plate, each of said flanges being adjacent an end opening; a plurality of number plates with each number plate positioned across an opening and having marginal portions extending over marginal portions of the base plate around said opening, said number plates being located on the same side of said base plate as said flanges and located between said flanges, said number plates being transparent at a portion thereof defining a numeral; a pair of holding members located against the base plate and adjacent each series of said aligned ends of the

openings, each of said holding members including a plurality of lateral portions each adapted to abut against the adjacent end of a number plate and prevent substantial displacement of the number plate in a direction toward the holding member, a plurality of extended fingers adjacent the edges of said number plates with a finger being located between an adjacent pair of number plates to prevent substantial lateral displacement thereof toward each other, and lips with each lip overlying at least a portion of the side of a number plate that is opposite the base plate to prevent substantial displacement of said number plate away from the base plate, said holding members including an end portion extending through an opening in each flange and bent up to prevent longitudinal displacement of the member and a lateral portion bent around an extended portion on each flange to prevent lateral displacement of said member; a resilient member attached to each flange and bearing against the adjacent side of the adjacent number plate; an

electric light bulb within said structure; a socket therefor; a spring clamp upon which said socket is mounted; and a flange within said structure upon which said clamp is removably held, said flange being formed of a tongue struck from said box-like structure.

JOHN MITCHELL.
